HAIR CURLER

Edgar B. Gilleland, Pasadena, Calif.

Application April 1, 1946, Serial No. 658,676

6 Claims. (Cl. 132—33)

1

This invention relates to improvements in hair curlers and refers more particularly to a curling device particularly adapted for use by an individual without heat or chemicals such as are employed in beauty parlor operations.

The device has certain common features with curlers now sold and with which bobby pins are applied to the curls after they have been made up. The instant curler, however, employs a pin or clip of a different construction than the bobby pin and has other advantages including the ease with which the curl can be removed from the mandrel, facility of removing the clip from the curl and the accessibility of the plunger for manipulating the clamping member which holds the end of the strand of hair during the forming of the curl.

Among the objects, therefore, of the invention is to provide an improved type of hair curler equipped with a fluted mandrel having a hair clamping member depressed within one of the fluted grooves whereby breaking of the hair ends is minimized and the curls after being formed on the mandrel are easily removed without loosening.

Another object is to provide a curler whose clamping member for the hair strands can be actuated in any position by a plunger device.

A further object is to provide an improved type of pin or clip for holding the curl after it has been removed from the mandrel.

Other and further objects will be apparent from the following description.

In the accompanying drawings which form a part of the instant specification and are to be read in conjunction therewith, and in which like reference numerals indicate like parts in the various views,

Fig. 1 is a side elevational view of a hair curler with a lock of hair curled on the mandrel and a clip in position to be applied to the curl,

Fig. 2 is a sectional view of the device shown in Fig. 1,

Fig. 3 is a view taken along the line 3—3 in Fig. 2 in the direction of the arrows,

Fig. 4 is a view taken along the line 4—4 in Fig. 2 in the direction of the arrows,

Fig. 5 is a view of a curl with the pin or clip applied, and

Fig. 6 is a side view of the improved type of pin or clip shown in Figs. 1 and 5.

Referring to the drawings and particularly to Figs. 1 and 2, the curler comprises a stationary support or holder 10 which has a tubular portion 10a and a bifurcated pin-holding portion 10b.

2

Into the tubular portion 10a is fitted a rotating mandrel 11 having a shoulder 11a which abuts against the holder 10. The mandrel is hollow and one end is tapered. The tapered portion is fluted by longitudinal grooves 11c. At the handle end of the mandrel is a collar 11d which has a knurled surface to facilitate its manual rotation. Extending into the hollow handle portion of the mandrel is a plunger 12. The forward end of the plunger 12 is bifurcated as shown at 12a in Fig. 4. Bearing in the bifurcated portions 12a and extending across the space between the parts is a pivot pin 13. This pivot pin may be rotatable or it may have a surrounding sleeve rotatable on the pin as shown at 13a in Fig. 2.

A hair clamping member in the form of a narrow strip 14 is bent over the pivot pin 13 and looped back as shown at 14a. The end of the bent back portion fits into a recess in the mandrel to form a spring which lies between the bifurcated portions 12a of the plunger. Just forward of the pivot pin 13 upon which the clamping member rests it has a reverse bend and is threaded through a slot in the wall of the mandrel at the base of one of the grooves 11c. The inner walls of the mandrel just ahead of the pivot pin 13 are shaped to conform with the bend in the clamping member as shown at 11e in Fig. 2, and abut the clamping member when the plunger is pushed forward. The spring formed at 14a serves to return the plunger 12 to its normal position after it has been actuated and to supplement this spring a coil spring 15 is positioned between plunger collar 12a and mandrel collar 11d. When a good grade of spring steel is used in the clamping member coil spring 15 will be unnecessary. To hold the assembly together a beveled ring 16 is pressed onto the mandrel at the base of its tapered portion and abuts the tubular section 10a of the holder.

To hold the curl of hair after it has been formed on the mandrel there is provided a pin shown separately in Fig. 6. In Fig. 1 the clip is mounted on the curler ready to receive the curl. In Fig. 5 the curl has been slipped from the curler onto the pin where it is held and may be adjusted as will hereinafter be explained. The pin consists of a loop portion 17a formed by doubling a wire back upon itself and fastening the free end upon the standing part by welding, brazing or winding as shown best in Figs. 1 and 6. The free end 17b is bent back through the loop in the manner best shown in Fig. 6 so the plane of movement of the free end 17b is substantially normal with the plane of the loop.

In applying the pin or clip 17 to a curl it is first attached to the curler in the manner shown in Fig. 1 by adjusting the loop 11a in the slot between the bifurcated ends 10b of the holder and inserting the free end 17b into the hollow end of the mandrel. Since the wire pin is made of resilient wire, which tends to hold the form shown in Fig. 6, the spring in the wire will hold the clip in position. Plunger 12 is then pressed forwardly which causes the clamping member to assume the dotted line position shown in Fig. 2. A strand of hair is then placed between the clamping member and mandrel and the plunger retracted to permit the clamping member to grip the hair strand, as shown in full line position in Fig. 2. The end of the strand of hair lies between the clamping member and the mandrel with the hair bent into the groove. The mandrel is then rotated manually by turning the knurled collar 11d which winds the hair 18 in the form of a curl on the outer surface of the mandrel as shown in Fig. 1. When the curl has been formed, it is easily slipped from the mandrel to the clip at which time the clip is removed from the curler. The curl is held on the clip in the manner shown in Fig. 5. Depressing the clamping member below the tapered surface of the mandrel upon which the curl is wound facilitates its removal from the mandrel to the pin without loosening the curl. In conventional curlers of this type the member which holds the hair strand against the mandrel is clamped directly against the outer tapered surface of the mandrel and when the hair is wound about the mandrel and clamping member to form the curl it is difficult to remove the curl onto the pin without slightly reversing the rotation of the mandrel to loosen the curl. In the instant device locating the clamping member within one of the fluted grooves obviates this difficulty.

After the curls have been slid onto pins or clips the hair may be spread to conceal the pins and the curls kept in tight form without showing the clips. Besides having a form which prevents slipping of the curls, the pins or clips do not readily slip off of the curls unless removed manually. This is due primarily to the manner in which the free end of the pin extends through the loop portion. In this regard the pins are different from the bobby pin type of clip which relies primarily upon resiliency of the metal of the pin to hold it upon the curl.

It will be seen that the objects have been accomplished since there has been provided a curler upon which curls of hair can be wound and easily removed. The clamping member may be actuated in any position by reciprocation of the plunger located at the rear of the mandrel. The improved type pin or clip holds the curl intact after it has been formed, and although it can be easily removed from the curl, it is less likely to fall off of the curl than are pins or clips of the conventional bobby pin type.

From the foregoing it will be seen that this invention is one well adapted to attain all of the ends and objects hereinabove set forth together with other advantages which are obvious and which are inherent to the structure.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter

herein set forth or shown in the accompanying drawings is to be interpreted as illustrative and not in a limiting sense.

I claim:

5. In a hair curler the combination with spaced apart members, one a stationary holder, the other a tapered mandrel upon which the hair is curled, said mandrel rotatable in the stationary holder, a reciprocable plunger fitting the handle 10 end of the mandrel, a resilient hair clamping finger having one end secured within the plunger and the other end normally disposed against the mandrel, and a connection between said plunger and said finger to raise said other end of the finger from the tapered mandrel surface responsive to movement of the plunger axially of the mandrel...
15. 2. A hair curler as in claim 1 in which the resilient clamping finger is pivoted upon a pin within the plunger and is looped and anchored within the plunger to form a spring tensioned to urge the plunger toward its rearward position...
25. 3. In a hair curler, a hollow mandrel for holding hair thereabout, said mandrel having an aperture in one side intermediate its ends, a spring finger extending through said aperture and having one end anchored in the bore of the mandrel, the portion of said finger outside the mandrel being disposed longitudinally of the mandrel and normally maintained by the spring tension against the side thereof, a plunger in the bore of the mandrel movable axially thereof, and means on the plunger to apply pressure to the spring finger at a point inside the mandrel responsive to axial movement of the plunger thereby to displace the outer end of said finger from against the mandrel...
35. 4. In a hair curler, a hollow mandrel for holding hair thereabout, said mandrel having an aperture in one side intermediate its ends, a spring finger extending through said aperture and having one end anchored in the bore of the mandrel, the portion of said finger outside the mandrel being disposed longitudinally of the mandrel and normally maintained by the spring tension against the side thereof, a plunger in the bore of the mandrel movable axially thereof, said plunger having bifurcations straddling the portion of said finger inside said mandrel and carrying a cross pin engaging the straddled part of the spring, said pin effective upon axial movement of the plunger to apply pressure to the spring to deform same to displace the outer end thereof from against the mandrel...
45. 5. In a hair curler, a hollow mandrel for holding hair thereabout, said mandrel having an aperture in one side intermediate its ends, a spring finger extending through said aperture and having one end anchored in the bore of the mandrel, the portion of said finger outside the mandrel being disposed longitudinally of the mandrel and normally maintained by the spring tension against the side thereof, a plunger in the bore of the mandrel movable axially thereof, said plunger having bifurcations straddling the portion of the finger inside the mandrel, a cross pin between the bifurcations, said spring having a reverse bend embracing said pin on three sides and tending to maintain said plunger in a predetermined position in the mandrel...
55. 6. In a hair curler, a hollow mandrel for holding hair thereabout, said mandrel having an aperture in one side intermediate its ends, a spring finger extending through said aperture
65. 7. In a hair curler, a hollow mandrel for holding hair thereabout, said mandrel having an aperture in one side intermediate its ends, a spring finger extending through said aperture and having one end anchored in the bore of the mandrel, the portion of said finger outside the mandrel being disposed longitudinally of the mandrel and normally maintained by the spring tension against the side thereof, a plunger in the bore of the mandrel movable axially thereof, said plunger having bifurcations straddling the portion of the finger inside the mandrel, a cross pin between the bifurcations, said spring having a reverse bend embracing said pin on three sides and tending to maintain said plunger in a predetermined position in the mandrel...
70. 8. In a hair curler, a hollow mandrel for holding hair thereabout, said mandrel having an aperture in one side intermediate its ends, a spring finger extending through said aperture
75. 9. In a hair curler, a hollow mandrel for holding hair thereabout, said mandrel having an aperture in one side intermediate its ends, a

and having one end anchored in the bore of the mandrel, the portion of said finger outside the mandrel being disposed longitudinally of the mandrel and normally maintained by the spring tension against the side thereof, a plunger in the bore of the mandrel movable axially thereover, said plunger having bifurcations straddling the portion of the finger inside of the mandrel, a cross pin between the bifurcations, said spring bent to form a sloped camming surface adjacent said pin whereby axial movement of the plunger causes said pin to bear against said surface and displace the outer end of the spring finger from against the mandrel.
